A circular seal or stamp. In the center is a stylized letter 'P'. Above the 'P' is the letter 'W'. Below the 'P' is the number '18'. To the left of the 'P' is the letter 'W' with a superscript '3'. To the right of the 'P' is the letter 'W' with a superscript '2'. To the right of the 'P' is the name 'R. Cannon'. Below the 'P' is the name 'J. A. Misland'. At the bottom of the seal, the name 'Fannie Goldsborough' is written, followed by 'Attys.'.

UNITED STATES PATENT OFFICE.

ROBERT CANNAN AND JOSEPH A. MISLAND, OF BROOKLYN, NEW YORK.

DOUBLE-THROW SWITCH.

1,025,454.

Specification of Letters Patent.

Patented May 7, 1912.

Application filed June 7, 1907. Serial No. 377,817.

To all whom it may concern:

Be it known that we, ROBERT CANNAN, a citizen of the United States, residing at Brooklyn, in the county of Kings and State 5 of New York, and JOSEPH A. MISLAND, a citizen of the United States, residing at 325 Essex street, Brooklyn, county of Kings, and State of New York, have invented certain new and useful Improvements in Double-Throw Switches; and we do hereby declare the following to be a full, clear, and exact description of the invention, such as will enable others skilled in the art to which it appertains to make and use the same.

15 Our invention relates to improvements in double-throw switches, and it has had its practical embodiment in a double-throw snap switch particularly adapted for use in connection with a system of train lighting in 20 which there is used a generator, a storage battery, and a current and voltage regulator.

The particular system in connection with which our switch has been designed, is the system illustrated and described in United 25 States Letters Patent to Patrick Kennedy, Ser. No. 800,114, dated September 19, 1905, but the improvements are applicable to double-throw switches generally, and particularly to snap-switches.

30 The nature of our improvements will be understood from a consideration of the following description in connection with the accompanying drawings, in which—

Figure 1 is a side elevation of the complete switch; Fig. 2 is a detail on an enlarged scale showing the construction and arrangement of locking dogs for the switch lever; Fig. 3 is a cross-section of the switch lever showing the operating handle and 40 springs. Fig. 4 is a plan view showing the relative positions of the contact terminals and switch parts.

The switch A comprises a base plate *a* of insulating material, on which are mounted 45 the stops *b* and *b'*, also of insulating material and against which the respective ends of the switch lever strike when the switch is thrown; the auxiliary pairs of contact terminals *h* and *h'* having the binding-posts *i* and *i'*; the pair of main contact terminals *o* having the binding posts *p*, and the support *k* for the bent switch lever *l*, the locking dogs *m* and *m'*, and the operating handle *n*. The support *k* comprises two standards *r* secured 50 to the base-plate *a* and provided with journals *r'* for the pivot pin *r''*, on which the

bent switch lever *l* and the operating handle *n* are separately pivoted. These two standards are spaced apart by a block *s* and the pins *r''* extend through this block and the lateral projections *r'''* of the standards and serve as pivots for the locking dogs *m*, *m'*, which are set into slots in one of the standards *r*. Each locking dog is provided with a head which takes over the appropriate lug *t* on 60 the switch lever, each of these lugs being provided on its upper surface with a small plate of steel *t'* to prevent wear, the main portion of each projection being cast integral with the brass switch lever. The 65 springs *u* and *u'* are coiled about the pins *u''* extending between the two standards *r* and these springs have one end resting on the base *a* and the other pressing against a pin *u'''* on the locking dogs, tending to hold 70 those dogs in the upright position shown in Fig. 2. Each dog is provided with a stop *u'''* to prevent its rotation beyond the upright position.

The longer arm of the switch lever *l* has 80 at its outer end an enlarged portion *l'* which is intended to engage the pair of main contact terminals *o* and which is cast hollow to save brass and lessen the weight, and which also serves to contact with the stop *b*. Back 85 of this enlarged portion and on the underside of the switch is a countersunk recess lined with insulating material, in which is set the U-shaped contact piece *l''* for the auxiliary contact terminals *h'*, and this contact 90 piece is held in place by a plate *l'''* screwed to the underside of the switch lever and suitably insulated therefrom, as shown. Above this contact piece *l''* and within the 95 switch lever is formed a recess which contains the pin *l''''*, the axis of this pin lying between the upturned portions of the U-shaped contact piece *l''*. The coiled spring *l''''* extends from this pin to the operating handle, and is attached to the handle at a point just 100 above the pivotal axis thereof, the relation of the axis of the pin *l''''* to the point of attachment being such that they are on substantially the same horizontal line when the handle *n* is in a vertical, and the long arm of 105 the switch lever in a horizontal position. The spring *v* is secured to the operating handle at a point opposite the point of attachment of the spring *l''''* and equally distant from the axis of the handle, and extends to 110 a pin *v'* which has the same relation to the other auxiliary contact piece *v''* that the pin

⁵ ¹⁰ ¹⁵ ²⁰ ²⁵ ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵

l^5 has to the piece l^3 . The contact piece v^2 is constructed in the same manner as the contact piece l^3 , is equally distant from the pivotal center of the switch lever, and is similarly supported and insulated in the short arm of the switch lever. This short arm has an extended toe l^7 adapted to contact with the stop b' . It will be understood that the switch lever and the operating handle are independently movable with respect to one another.

The double cam w is set over a squared projection on one side of the hub of the operating handle n , as shown in dotted lines in Fig. 3, and is further secured to that handle by the rivet n' . The lower end of this cam straddles the yoke l^8 , joining the sides of the switch lever, and is provided with the toes w^2 and w^3 , which operate the locking dogs m' and m , by engaging the pins u^3 and m' and m , thereby turning the dogs on their pivots against the action of the springs u' and u . The relative arrangement of these parts is indicated by dotted lines in Fig. 2.

In operation, if the switch is in the position shown in Fig. 1, and it is desired to throw it to the reverse position, the handle n is turned on the pin r^2 , thus putting the spring l^6 under tension and at the same time gradually raising the point of attachment of the spring v above the horizontal line through the center of the pin v' . The parts are so arranged that when the handle has been brought to a vertical position and the switch lever is in the position shown in Fig. 1, the point of attachment of the spring v is substantially on a horizontal line with the center of the pin v' , and at this point the relation between the toe w^2 and the pin u^3 on the dog m' is as shown in Fig. 2. As the handle is moved beyond the vertical the toe w^2 engages the pin u^3 and turns the dog m' on its pivot against the spring u' and finally withdraws the dog from the projection t . At this time the spring l^6 is under tension, tending to pull the long arm of the lever down and the spring v has passed the center and is also under tension, tending to pull the short arm of the lever up. That is to say, tension is then applied to both springs in directions such as to create by them two separate turning moments in the same sense, on opposite sides of the fulcrum. The result is that on the release the switch is violently thrown to a position in which the circuits through the main terminals o and the auxiliary terminals h' are completed.

For the particular purpose for which this switch has been designed the main terminals o are necessary in connection with the auxiliary terminals h' , but it will be obvious that the mechanism by which the switch is thrown from one position to the other is not at all dependent upon the use of these two sets of terminals and the invention may

be applied to other types of double throw and snap-switches.

What we claim is:—

1. In a double-throw snap switch, a switch lever, sets of contact terminals in position to be electrically connected by said switch lever in its respective circuit-closing positions, two springs connected to said switch lever on opposite sides of its fulcrum, an operating handle pivoted on the fulcrum of the lever and to which the other ends of said springs are connected on opposite sides of its pivotal axis, lugs on said lever, locking-dogs pivotally supported in position to engage said lugs, and a double cam connected to said handle to turn the locking-dogs and release the switch lever after the tension has been applied, substantially as described.

2. In a double-throw snap switch, a bent switch lever, main contact terminals in position to be electrically connected by the said switch lever in one circuit-closing position, an auxiliary circuit-closing piece supported on, but electrically insulated from, each arm of the switch lever, auxiliary circuit contacts in position to be closed by said auxiliary contact pieces, two springs connected to said bent switch lever on opposite sides of its fulcrum, an operating handle pivoted on the fulcrum of the switch lever and to which the other ends of said springs are connected on opposite sides of its pivotal axis, a double cam secured to said handle, lugs on the switch lever, and pivoted spring-actuating locking-dogs engaging said lugs and operated by said cam to release the lugs after the tension has been applied, substantially as described.

3. In a double-throw snap-switch, a bent lever provided with lugs on opposite sides of its fulcrum, spring actuated locking dogs adapted to engage said lugs in respective circuit-closing positions, a pivoted operating handle, spring connections between the operating handle and the switch lever, and a double cam carried by the operating handle and adapted to actuate the locking dogs to release the switch lever after the spring connections have been put under tension by the movement of said handle, substantially as described.

4. In a double-throw snap-switch, a bent lever provided with lugs on opposite sides of its fulcrum, spring-actuated locking dogs adapted to engage said lugs in the respective circuit-closing positions, a pivoted operating handle, springs connecting the operating handle to the switch lever on opposite sides of its fulcrum and a double cam carried by the operating handle and adapted to actuate the locking dogs to relieve the switch lever after the springs have been put under tension by the movement of said handle, substantially as described.

5. In a double-throw snap switch, the bent lever *l* fulcrumed in the standards *r* and provided with the lugs *t*, pivoted locking-dogs *m* and *m'* engaging said lugs, the handle *n* pivoted on the fulcrum of the bent lever and connected to the two arms thereof by the springs *l*^o and *v*, and the double cam *w* connected to the handle and having the toes *w*² and *w*³ adapted to turn the locking-dogs to release the switch lever after tension has been applied to the springs, substantially as described.

10 6. In a snap switch for so controlling two electric circuits that when one circuit is closed the other is open, a base carrying circuit terminals for the two circuits, a bell-crank switch lever fulcrumed on the base between

the terminals, an actuating handle pivoted on the fulcrum of the lever, two springs connecting the two arms of the switch lever to 20 the actuating handle on opposite sides of its fulcrum, latches for restraining the switch lever, and a latch-releasing device moving with the handle to release the latches after the springs have been put under tension by 25 the movement of the handle.

In testimony whereof we affix our signatures, in presence of two witnesses.

ROBERT CANNAN.
JOSEPH A. MISLAND.
